METHOD AND APPARATUS FOR INTERCONNECTING MANIFOLD SETS OF STATIONERY

Louis Jensen, Chicago, Ill., assignor to United Autographic Register Co., a corporation of Illinois

Application January 12, 1939, Serial No. 250,644

17 Claims.

(Cl. 154—42)

This invention relates particularly to a method and apparatus for interconnecting separate sheets or manifold sets of stationery into a continuous strip so that it may be fed through a typewriter or similar machine readily.

The primary object of the invention is to provide a method which may be carried out in an automatic machine to manufacture stationery of the type shown in MacFarland Patent No. 2,089,128, issued August 3, 1937. This stationery comprises a series of packets of forms provided with interleaved carbon and having the packets connected end to end by marginal flaps.

A further object of the invention is to provide an automatic machine wherein stationery of the type referred to, known in the trade as "Multi-Linkt," may be made accurately and inexpensively.

The invention is illustrated in a preferred embodiment in the accompanying drawings, in which—

Figure 1 is a front elevational view of a machine embodying the invention; Figure 2, a broken plan view of the same; Figure 3, a plan view of stationery which can be assembled by the machine; Figure 4, a broken sectional view of the left end of the machine, as viewed in Figure 1; Figure 5, a broken sectional view of the right end of the machine, as viewed in Figure 1; Figure 6, a broken sectional view, taken as indicated at line 6 of Figure 2; Figure 7, a fragmentary sectional view on an enlarged scale showing the flipper mechanism; Figure 8, a fragmentary view of the gearing and drive mechanism; and Figure 9, a side elevational view on an enlarged scale of the stationery illustrated in Figure 3.

In the embodiment illustrated, A designates a main frame provided with supporting legs A'; B, conveyor and aligning mechanism which receives the separate manifold sets; C, punching mechanism which may be provided to perforate the top marginal portion of the stationery; D, a gluing device for applying a strip of adhesive to the top marginal portion of the manifold set; E, an endless belt conveyor which receives the manifold sets from the conveyor B; F, an endless belt conveyor provided with feed-pins which is assisted by shorter conveyor belt's F' in removing the sets seriatim from the conveyor E; G, flipper for bringing the ends of the sets in proper overlapped condition; and H, presser mechanism for compressing the adhesively joined portions of the sets.

The frame A may be of any suitable construc-

tion and preferably is a metal bed in which the mechanism is mounted. The bed is supported on suitable standards A'. As shown in Figure 1, an electric motor 10, through a suitable reduction gear drive 11, drives a belt 12 on a pulley 13 provided on a main drive shaft 14.

As best shown in Figures 2, 6, and 8, a sprocket chain 15 transmits power from the shaft 14 to a shaft 16. Speed reducing idler gears 17 and 18 drive gear 19 on a shaft 20 from a gear 16a on the shaft 16.

The gear 19 drives gear 21 which has a bevel gear 22 in mesh with a bevel gear 23 on shaft 24 which drives the presser members H by means of bevel gears 25 and 26. Gear 28 is provided with a spur gear 27 which drives idler gears 28 and 29 which in turn mesh with gear 30 provided on a drive shaft 31 for the conveyors F and F'.

The gear 21 also drives an idler gear 32 which drives a gear 33 on a shaft 34 of the flipper mechanism G. The other end of the shaft 34 is provided with a spur gear 35 which drives a gear 36 on a lower shaft 37 of the flipper mechanism. The gear 33 through an idler 38 drives gear 39 on shaft 40 of the flipper mechanism.

As shown in Figure 2, the shaft 16 is provided with a hand wheel 16b for convenience in making timing adjustments on the machine.

As indicated by the dotted lines in Figure 8, the shaft 16 is provided with a bevel gear 41 which meshes with a bevel gear 42 and drives shaft 43 of the conveyor E.

As shown in Figure 2, the shaft 20 is provided with gear 44 which meshes with an idler gear 45 having a bevel gear 46 to drive a shaft 47 of the conveyor B.

The shaft 20 is further provided with a bevel gear 48 which meshes with a bevel gear 49 and drives the punching or perforating machine C. Also, a gear 50, through idler gears 50a, drives jack shaft 51 which is provided with a pulley 51a to drive a friction cylinder 52 by means of a belt 51b which passes around pulley 52a.

The conveyor and aligning mechanism B, best shown in Figures 2, 4, and 5, has several components. A pair of endless sprocket chains 53 is driven from the shaft 47 by means of sprocket wheels 53a. The belts are provided at regularly spaced intervals with headed feed-pins 53b which engage the lateral edge of a set of manifold stationery and carry it transversely with the belt. The rear ends of the belts are reefed around an idler sprocket wheel 53c.

The manifold sets of stationery, as will be understood, by reference to Figures 3 and 9, comprise packets of stationery and interleaved carbon 54. Preferably the bottom sheet of the packet has a trailing flap 54a which in the final assembly is pasted to the top marginal portion of the succeeding packet. The packets are shown provided with register perforations 54b which may be made in the set before it is placed on the belt 53, but preferably are made by the punching mechanism C, described below. These perforations are useful in the feeding operations of the present machine and also are desirable for filing purposes after the forms have been used. The dotted lines in Figure 3 each indicate lines of weakening in the stationery to facilitate pulling the forms apart after use in a typewriter.

A fixed upwardly extending guide-member 55 is provided along one side of the conveyor belts 53. Preferably the cylinder 52 is journalled between the belts 53 so that its upper face brushes lightly against the underside of the sets 54 and urges them lightly against the guide 55 as they are moved transversely into the machine. An adjustable guide mechanism 56 is provided above the conveyor and aligning mechanism B to hold the sets in flat condition. The guide mechanism is supported by suitable brackets 56a and has a socket bar 56b which loosely confines a series of glass spheres 57 so that they may press the sets 54 lightly against cylinder 52 without impeding the movement of the sets.

The punching mechanism C is of known construction and accordingly is not shown in detail. A pair of punching heads moves downwardly in an arc in the direction that the stationery travels so that the punching is done without interfering with the movement of the sets.

The gluing mechanism D is also of known construction and is shown somewhat diagrammatically in Figures 2 and 5. The glue is placed in a fountain 58 and suitable contact disks 58a, driven from the shaft 47, transmit a narrow strip of adhesive material to the top marginal portion of the sets, just above the perforations 54b. Suitable mechanism is provided to lift the disks 58a during the intervals that the sets are not in adhesive receiving position.

The conveyor E comprises an endless belt 59 which is disposed near the ends of the belts 53 and driven from the shaft 43 by means of a pulley 59a. The belt passes around an idler pulley 59b on a shaft 59c and thence under a tensioning pulley 59d. A fixed abutment guide 60, see Figure 5, is provided to limit the transverse travel of the sets 54. The conveyor E is geared to travel at a considerably faster rate than the belts 53 so that when the sets are partially projected over a table 61 into contact with the conveyor E, their travel is accelerated so that they are drawn clear of the headed pins 53b on the conveyor belts 53 and are thrown rather sharply against the guide 60. The continued light brushing effect of the conveyor E on the bottom of the forms holds one lateral edge of the sets in proper alignment against the guide 60. Above the conveyor E are provided suitable guide-members 62 and 63 to keep the sets flat and in light contact with the conveyor.

As best shown in Figures 2 and 6, the endless link-belt 64 of the conveyor F is driven by a sprocket wheel 65 on the shaft 31 and its rear end passes around idler sprocket 64a on a shaft

66. The belt is provided with feed-pins 66 which are adapted to engage the perforations 54b in the sets as they are delivered into position seriatim by the conveyor E.

It will be noted that the conveyor F is disposed at right angles to the conveyors B and E and extends beneath the conveyor belt 59. A cam wheel 67 is provided on the shaft 34 to oscillate a rock arm 68 which is pivoted at 68a and urged downwardly by a tension spring 68b. The rear end of the rock arm 68 is provided with a shoe 69 which is adapted, when permitted to swing down by the cam 67, to depress the top marginal portions of the sets and press the perforations 54b over the pins 66. As will be understood, the shaft 34 rotates in timed relation to the movement of the belt F so that the separate sets are picked up seriatim in a continuous overlapping series by the conveyor F. The pins 66 are spaced on the chain 64 so that there is just room for the trailing flap 54a of the advanced set of forms to lie flatly against the belt and clear the next set of pins. Thus it will be understood that the top marginal portion of the next set of forms will initially overlap the trailing flap of the preceding set of forms and the exposed adhesive surface is not in contact with the flap.

After the sets travel over the flipper mechanism G, described below, they are brought into contact with a pair of endless conveyors F', disposed on the flanks of the chain conveyor F. These belts are driven by pulleys 70 on the shaft 31, passing around rear idler pulleys 71 on a shaft 71a, and are held taut by tensioning pulleys 71b.

The flipper mechanism G will best be understood by reference to Figures 2, 6, and 7. As was mentioned above, the trailing flap 54a is initially below the top marginal portion of the succeeding set of forms and the purpose of the flipper mechanism is to lift up the flap and bring its lower face into contact with the adhesive on the top marginal portion of the following set of forms. This operation is accomplished while the sets are moving continuously and is done by arms 72 arranged on the shafts 34, 37, and 40 which rotate in timed relation to the conveyor F. A pair of arms 72 is adjustably mounted on the shaft 34 so as to rotate downwardly and prevent the front portion of the preceding set from being disturbed during the flipping operation. Another pair of arms 73 is mounted on the shaft 37 so as to rotate upwardly and strike the rear portion of the set upwardly so that the flap 54a will be drawn out from under the top marginal portion of the following set and then be brought into adhesive contact with the adhesive strip. Another arm 74 is carried by the rotating shaft 40 so as to swing down and prevent the front of the succeeding set from being displaced from the pins 66 during the flipping operation. A pair of yielding guide-fingers 75 is provided on a cross-shaft 76 to smooth out the linked strip as it moves onto the auxiliary conveyors F'.

The linked strip of sets finally passes under the presser members H, see Figures 1, 2, and 6. Only three of the double acting members are shown for the purpose of illustration, although any desired number may be used. Normally five sets are desirable to produce the best results. As the pressers are all of similar construction and are driven from the shaft 24 by means of the bevel gears 22, 25, and 26, only one will be described. Each of the members has a square shaft 77 which is driven in timed relation to the conveyor F. Two cross-bars 78 are mount-

ed in opposed relation and have soft rubber inserts 79 to engage the adhesively connected areas of the advancing strip. The bars are yieldingly mounted for limited movement on push rods 80 and are urged outwardly by means of compression springs 81. The presser members are timed to rotate so that one or the other of the cross-bars on each shaft 77 will engage the advancing flaps 84a and press them firmly against the adhesive material on the front marginal portion of the set to which it is connected.

The operation of the machine is briefly as follows: the sets of manifold stationary are placed on the conveyor B and moved transversely under the punching device C and the gluing device D; the sets are then passed on to the conveyor E, accelerated in movement, and thrown against the guide 80; the direction of travel is then changed from transverse to forward by the shoe 88 pressing the ends of the sets seriatim into engagement with the forwardly moving pins 86; as the overlapped forms advance, the flipper mechanism strikes the flap of the preceding forms up into superposed engagement with the adhesive strip on the succeeding forms and the pasted joint is compressed by the presser members H; and the strip is then delivered from the machine by the conveyors F and F' where it may be stored in rolls or zigzag folded, as desired.

The foregoing detailed description has been given for clearness of understanding only, and no unnecessary limitations should be understood therefrom, but the appended claims should be construed as broadly as permissible, in view of the prior art.

I claim:

1. The method of interconnecting manifold sets of stationery sheets into tandem relation, which comprises: moving the sets seriatim into longitudinal spaced relation with the rear marginal portion of one of the sheets in an advanced set of forms lapping a front marginal portion of a sheet in the next succeeding set of forms; and connecting the overlapping sheets, while the sets are continuously advancing forwardly.

2. The method of interconnecting manifold sets of stationery sheets into tandem relation, which comprises: moving the sets transversely seriatim into longitudinal spaced relation with the rear marginal portion of one of the sheets in an advanced set of forms lapping a front marginal portion of a sheet in the next succeeding set of forms; and connecting the overlapping sheets, while the sets are continuously advancing forwardly.

3. The method of interconnecting manifold sets of stationery sheets into tandem relation, which comprises: moving the sets transversely and applying adhesive to the front marginal portion of the sets, seriatim; bringing the sets into longitudinal spaced relation seriatim with the rear marginal portion of one of the sheets in an advanced set of forms underlying the front marginal portion of the next succeeding set of forms; lifting the underlying rear marginal portion of said sheet in the advanced set of forms from underlying to overlapping position; and pressing the overlapped portion of the sheet against the adhesive.

4. The method of interconnecting into tandem relation manifold sets of stationery sheets having front marginal perforations, which comprises: aligning the front edge portions of the sets while moving them transversely; changing the direction of movement and overlapping par-

tially and aligning the sets in longitudinal relation with respect to said perforations, seriatim; and connecting the overlapped portion of one of the sheets in the advanced set to the front marginal portion of the next succeeding set.

5. A method as specified in claim 4, including the steps of applying adhesive to the front marginal portion of the sets, above the perforations, while they are moving transversely; and pressing the overlapped portion of the advanced sheet against said adhesive while the sets are advancing forwardly.

6. Apparatus for linking manifold sets of sheets, comprising: conveyor-means for moving the separate sets transversely; a conveyor angularly disposed to the conveyor-means and operating in timed relation thereto to receive the sets singly seriatim from said conveyor-means and advance them in partially overlapped longitudinally spaced relation; and means for connecting the overlapped marginal portions of the sets as they are advanced continuously by the last mentioned conveyor.

7. Apparatus as specified in claim 6, in which the means for connecting the sets comprises apparatus for applying adhesive to the front marginal portion of the sets as they are moved transversely, and a presser device for pressing the overlapped marginal portions while the sets are advanced longitudinally by the conveyor.

8. Apparatus for linking manifold sets of sheets, comprising: an endless belt conveyor for moving the separate sets transversely; a second conveyor disposed at the delivery end of said first conveyor, and operating at a greater speed in timed relation thereto, so as to receive the sets and accelerate their transverse movement; a fixed guide disposed beyond the delivery end of said second conveyor for limiting the transverse movement of said sets; a third conveyor disposed at a right angle to the first mentioned conveyors and driven in timed relation thereto; and means for withdrawing the sets seriatim from the second conveyor onto the third conveyor in overlapped, longitudinally aligned, spaced relation.

9. Apparatus as specified in claim 8, including means for flipping the rear marginal portion of an advanced set over the front marginal portion of a succeeding set, as the sets are advanced longitudinally on the third conveyor.

10. Apparatus as specified in claim 8, including means for flipping the rear marginal portion of an advanced set over the front marginal portion of a succeeding set, as the sets are advanced longitudinally on the third conveyor; and means for pasting together the overlapped marginal portions of the sets.

11. Apparatus as specified in claim 8, in which the means for withdrawing the sets from the second conveyor comprises pins mounted on the third conveyor, and a presser device to engage perforations in the sets with said pins.

12. In a machine for linking manifold sets of stationery: an endless belt conveyor provided with means for receiving and carrying manifold sets in longitudinally spaced relation with the rear marginal portion of one set underlying the front marginal portion of the next succeeding set; and means operating through said conveyor and in timed relation thereto for flipping the rear end of the advanced set over the front marginal end of the succeeding set while the sets are being advanced on said conveyor.

13. A device as specified in claim 12, in which

the flipping means includes an arm rotating in timed relation to the movement of the conveyor so as to strike the underside of the rear portion of the advanced set and press it upwardly.

14. A device as specified in claim 12, in which the flipping means include an arm rotating in timed relation to the movement of the conveyor so as to strike the underside of the rear portion of the advanced set and press it upwardly, and a pair of guide-members rotating above the conveyor in timed relation thereto so as to prevent vertical displacement of the succeeding set and the front of the advanced set during the flipping operation.

15. Apparatus for linking manifold sets of 15 sheets, comprising: conveyor-means for moving perforated separate manifold sets transversely; means for applying adhesive material to the front marginal portion of the sets as they move transversely; an endless belt conveyor disposed at a right angle and driven in timed relation to said conveyor-means so as to receive the sets, said belt being equipped at regularly spaced intervals with feed-pins to engage the perfora-

tions in the sets; presser-means driven in timed relation to the belt conveyor to press the sets serially into contact with said feed-pins and start their forward movement with the front 5 marginal portion of each set initially overlapping the rear marginal portion of the preceding set; means for flipping the rear marginal portion of the preceding set to superposed position in contact with the adhesive on the following set; and means for pressing the adhesive joints as 10 the connected sets advance on said belt conveyor.

16. Apparatus as specified in claim 15, in which the means for pressing the adhesive joints comprises a plurality of bar-like members which are rotated in timed relation to the belt conveyor.

17. Apparatus as specified in claim 15, in which the means for pressing the adhesive joints comprises a plurality of bar-like members which are rotated in timed relation to the belt conveyor, 20 said bars being mounted in opposed pairs and yieldingly urged outwardly by means of compression springs.

LOUIS JENSEN.
